CLAIM

The ornamental design for a confection as shown and described.

DESCRIPTION

FIG. 1 is a perspective view of a confection embodying our design;

FIG. 2 is a front elevational view of the confection shown in FIG. 1;

FIG. 3 is a rear elevational view of the confection shown in FIGS. 1 and 2;

FIG. 4 is a left-side elevational view of the confection shown in FIGS. 1-3;

FIG. 5 is a right-side elevational view of the confection shown in FIGS. 1-4; and,

FIG. 6 is a top view of the confection shown in FIGS. 1-5. The different shades of grayscale shading are provided solely for the purpose of showing surface contours, and no specific color or tone difference is claimed. The dot-dash lines and the areas within the dot-dash lines show portions of the confection that form no part of the claimed design.
